UNITED STATES PATENT OFFICE

CHARLES E. GIBBS AND ALDEN B. LAWSON, OF BALTIMORE, MARYLAND

METAL CAR ROOF

Application filed March 22, 1929. Serial No. 349,106.

While our invention may be embodied in car roofs in general, we have elected to illustrate and describe it in connection with roofs for passenger cars.

5 Roofs with upstanding seams or joints have been used on passenger cars, but they are objectionable from many standpoints as, for instance, the difficulty of maintaining air and water tight joints when the car is running at a high speed against a storm. To overcome the objection to the upstanding seam the rigid flat seam type of roof formed of thick steel sheets was adopted for passenger cars, but in the use of this type of roof it 10 is necessary to make the assembly of the roof on the car before the inside ceiling or finish in the car is applied. Again, in making a repair to this flat seam roof, or to renew the roof on an old car, it is necessary to take down both the ceiling and the inside finish of the car in order to reapply the flat seam type of roof. Therefore, to reapply the present flat 15 seam type of roof there is not only the expense of removing and reapplying the interior ceiling and inside finish, but also considerable time is consumed in preparing for the application of such a roof and refinish- 20 ing the interior of the car after it is applied.

The primary object of our invention is to 25 provide a flat seamed roof for a passenger car of such construction and arrangement that in the event of a repair the repair to the roof may be made from the exterior of the car without disturbing the ceiling or inside finish 30 of the car; and another object of our invention is to provide a rigid flat seamed roof made of thick steel sheets and which is free from the objections to the roof structures heretofore in use; and with these and other 35 objects in view our invention consists of the parts and combination of parts as will be hereinafter set forth.

In the drawings:

40 Figure 1 is a detail perspective view of an upper and lower deck portion of a car to which our roof has been applied.

Figure 2 is an enlarged detail sectional view.

45 Figures 3, 4, 5 and 6 show several embodiments of my invention.

Figure 7 is a more or less diagrammatic view longitudinally of two roof sheets and a bow sheet applied to a car.

In the drawings the numeral 1 designates a 55 passenger car of any desired construction. In building new cars for our type of roof any desired form of carline may be used, but we prefer to make the carlines 2 with a horizontal top flange 3, and we prefer to have the top flange of the first carline near the end of 60 the car to face outwardly with the said flange projecting toward the end of the car. The other carlines throughout the length of the car we prefer to range so that the top flanges 3, 17, 25, 31 and 34 project toward the 65 other end of the car so that with the exception of one of the end carlines the top flanges of all of the carlines including the other end carline project in the same direction. We prefer that all of the carlines be coated with 70 a suitable cement before the roof is applied to the car, but this is optional with the car builder.

In practicing our invention we rivet the bow 75 end of the first roof sheet 5 to the flange 3 of the end carline 2 as at 6, and the other end of the sheet 5 is likewise riveted at 7 to the second carline 2, the extreme inner end of the sheet 5 projecting, preferably, beyond the end of the flange 3 of the second carline. 80 The next succeeding sheet 8 is riveted at 9 to the flange 3 of the third carline 2, the end of the sheet projecting beyond the flange 3. The bow end of the roof sheet 8 is then welded at 10 to the roof sheet 5 to one side of the rivets 85 7. The next roofing sheet 11 is applied by riveting to the next succeeding carline and welded at its bow end to the sheet 8 as has been described in connection with the securing of sheet 8, and the securing of the succeeding sheets of the roof of the car to the 90 other end of the car proceeds as described in connection with sheet 8.

The bow sheet 12 is preferably welded at 13 to the bow end of the sheet 5 and outside 95 of the line of rivets 6 the extreme outer end of the bow sheet 12 may be suitably riveted at 13' to an eaves molding 14 which is suitably secured to the end wall of the car.

We prefer to coat the underside of the roof 100

sheets with a suitable cement before they are applied, but, of course, this is optional with the builder.

Before applying the roof sheets we prefer

- 5 to place under the flange 3 of each carline a suitable insulating member 15, which member may be made of any suitable material, and the object of placing this insulating member in this position is to protect the usual roof insulation 16 from the heat incident to the welding of the car roof sheets, and before the roof sheets are applied we prefer to apply the roof insulation 16, which insulation is protected against the heat of the weld by the insulating member 15. While it is possible to eliminate the insulating member 15 we prefer to use it as in addition to the protection it affords during welding, it serves thereafter as an extra guard against heat exchange at the 10 joint and as a protective pad to prevent attrition of the material 16 from rubbing engagement with the carline and roof sheets, and it further serves as a dampener to reduce vibration and noise at this point.
- 20 25 In cars built for other types of roofs we have found in applying our improved roof to the carlines of such cars that the carlines are not in some cases particularly adapted to receive our improved roof, because the flanges 30 of the carlines do not always point in the same direction, therefore, in order to adapt the old carlines to receive our improved roof we apply an angle iron 17 to the carline 18 and secure it thereto by means of the rivet 19, as shown in Fig. 2, and in this connection it will be seen from the drawings that the far end of the sheet 20 is riveted at 21 to the angle bar 17, and that the next succeeding sheet 22 is applied as has been described in connection with sheet 8.

Another expedient for adapting old carlines for our improved roof is to apply to the usual plate 24 of the carline 23 an angle bar 25 to which the sheet 26 is riveted at 27, as shown in Fig. 3, and the succeeding sheet 28 is secured in the manner described in connection with applying sheet 8.

As shown in Figure 6 of the drawings in connection with the original carline 29 we can rivet an angle 30 to that carline with the top flange 31 of the angle spaced above the top angle 32 of the original carline forming an insulating space 33 between the two members, for a full welded roof.

55 60 We may also, as shown in Figure 5 in the drawings, rivet to the carline 34 a suitable insulating member 35 spaced below the top flange of the carline to form an insulating space 36 for a full welded roof.

65 As stated, in placing our improved roof on the old car it is necessary before proceeding with the application of the new roof to have the top flanges of the carlines pointing all in the same direction except the first one adjacent to the bow which, as has been explained,

is to be applied in the opposite direction for riveting new sheets. If some of the carlines have flanges in the old cars pointing in opposite direction, it is necessary to rivet to these old carlines the angles and plates as 70 herein described.

In building new cars the carlines are applied with the top flanges of the carlines pointing all in the same direction except the first one adjacent to the bow so that after 75 the first sheet has been riveted on the successive sheets can be applied as above described, riveting the far edge and welding the near edge to the top of the succeeding sheet, the welding joint being as near a rivet 80 as is possible.

In the application of our new roof the roof sheets are not only securely tied to the carlines making a rigid superstructure, but also eliminates the possibility of leakage near the 85 roof joints.

In applying and repairing roofs embodying our invention one of the major expenses incident to repairing a roof is eliminated, namely, the necessity of removing the ceiling and interior finish of the car. In using our improved car roof a repair may be made without disturbing or, in any way, removing or damaging the ceiling or interior finish.

Another important advantage of our invention is that it allows a roof to be built of comparatively thick steel sheets, of a thickness of .078", for example, to provide a roof rigid enough to be unaffected by weaving and twisting strains of the car and which does not require auxiliary bracing or reinforcing or necessitate the use of thin roof material formed with joints constructed to allow cushioning movements to compensate for weaving and twisting of the car, and which joints render the roof difficult to repair and to keep in leak-proof condition. Our construction not only avoids these objections, and provides a roof which is sufficiently stiff for the trainman to walk and stand upon without injury to it, but which is free from joints liable to leak and is capable of being applied or repaired, as stated, without the necessity of disturbing the ceiling and inside finish of the car in the working operation.

Of course, it is understood that the upper and lower deck roofs are of the same construction.

The term "near edge" means that edge of a roof sheet nearest the bow where application is started, and the term "far edge" means that edge of the roof sheet remote from such bow.

As shown in Figures 5 and 6, we may butt 125 weld the edges of contiguous roof sheets, the weld being designated at 37.

What we claim is:

1. In a car roof the combination with carline structures, a first roof sheet riveted at 130

both its far and near edge portions to two adjacent carlines, a second roof sheet riveted at its far edge portion only to a third carline and welded at its near edge to the far edge portion of the said first sheet, and additional roof sheets to complete the roof secured to succeeding carlines and sheets in a manner similar to the second sheet.

2. In a car roof the combination with carlines having flanges at their tops, of a first roof sheet riveted at both its far and near edge portions to two adjacent carlines, and resting on said flanges, a second roof sheet riveted at its far edge portion only to the flange of a third carline, and welded at its near edge to the far edge portion of the first sheet, and additional roof sheets to complete the roof secured to succeeding carlines and sheets in a manner similar to the second sheet.

3. In a car roof the combination with carlines having flanges at their tops, of a first roof sheet riveted at both its far and near edge portions to two adjacent carlines, and resting on said flanges, a second roof sheet riveted at its far edge portion only to the flange of a third carline, and welded at its near edge to the far edge portion of the first sheet, and additional roof sheets to complete the roof secured to succeeding carlines and sheets in a manner similar to the second sheet, the roof structure having a heat insulating zone underlying each carline flange to which a sheet is riveted.

4. In a car roof the combination with carline structures, a first roof sheet riveted at its far and near edge portions to two adjacent carlines, a second roof sheet riveted at its far edge portion to a third carline and welded at its near edge to the far edge portion only of the said first sheet and additional roof sheets to complete the roof secured to succeeding carlines and sheets in a manner similar to the second sheet, insulation material under the roof sheets, and an anti-friction heat nonconductor shield secured above the said insulation material in each zone of welding whereby the insulation is protected from undue wear and from the heat incident to welding.

5. In a car roof the combination with transverse carlines having top flanges extending laterally therefrom all pointing in the same direction longitudinally of the car except the first one at the bow, the flange of which points in an opposite direction, a first roof sheet riveted at its far and near edge portions to the flanges of the first and second carlines, a second roof sheet riveted at its far edge portion only to the flange on the third carline and welded at its near edge to the far edge portion of the first roof sheet, and additional roof sheets to complete the roof secured to succeeding carlines and sheets similar to the second roof sheet.

6. A car roof including an end carline having a flange projecting toward one end of the car, and a series of carlines having flanges all extending toward the opposite end of the car, a first roof sheet riveted at one end to the flange of the first-named carline and at its opposite end to the flange of the next carline of the series, and other roof sheets successively secured together and to the carlines at their contiguous edges respectively by riveting and welding in the direction toward the second-named end of the car.

7. A car roof including carlines, a plurality of roof sheets secured together and to the carlines at their contiguous edges by riveting to the carlines and welding to each other, insulating material beneath the roof sheets, and a shield of friction reducing and heat non-conducting material disposed in the welding zone immediately below each sheet and between said sheets and the said insulating material.

8. A car roof comprising a series of carlines having flanges, the carline at one end of the series having its flange projecting toward the adjacent end of the car and the remaining carlines of the series all having their flanges projecting toward the opposite ends of the car, an eaves molding at each end of the car beyond the adjacent end carline of the series, a bow sheet riveted to each eaves molding and the adjacent end carline, a first roof sheet riveted at its near end edges to the flange of the first-named carline and at its far end edge to the flange of the next adjacent carline of the series, a second roof sheet welded at the near edge to the far edge of the first roof sheet and riveted at its far edge to the flange of the third carline, and other roof sheets secured to each other and the remaining carlines of the series in a manner similar to the second roof sheet.

9. The method of applying a car roof, which consists in providing on the car a series of transverse flanged roof supporting carlines, with the flange of one of the end carlines of the series projecting toward the adjacent end of the car and the flanges of the second and all the other carlines of the series projecting toward the opposite end of the car, riveting the near and far edge portions of the first roof sheet respectively to the flanges of the first and second carline, welding the near edge of the second roof sheet to the far edge of the first sheet and riveting the far edge of the second roof sheet to the flange of the third carline of the series, and then applying the third and successive sheets to the flanges of succeeding carlines and to each other in a manner similar to the second sheet from said third carline to the final carline at the second-named end of the car.

10. The method of applying a car roof to a car having a series of roof supporting car-

lines, some of which are provided with upper horizontal flanges and others of which are devoid of such flanges, which consists in providing the second-named carlines with flanges attached thereto, riveting the near and far edge portions of the first roof sheet respectively to the flanges of the first and second carlines, welding the near edge of the second roof sheet to the far edge of the first sheet and riveting the far edge of the second roof sheet to the flange of the third carline of the series, and then applying the third and successive sheets to the flanges of succeeding carlines and to each other in a manner similar to the second sheet from said third carline to the final carline at the second-named end of the car.

11. A car roof including a transverse carline having a lateral flange and a roof sheet secured at one edge to the contiguous edge of said flange by riveting and an adjacent roof sheet overlapping the edge of the first and united thereto by welding.

In testimony whereof we affix our signatures.

CHARLES E. GIBBS.
